(57) **CLAIM**

The ornamental design for a tape measure marking accessory, as shown and described.

DESCRIPTION

FIG. 1 is a front perspective view showing our new design. FIG. 2 is a top plan view thereof.

FIG. 3 is a bottom plan view thereof.

FIG. 4 is alternate front perspective view thereof as connected to a tape measure to illustrate environment, the tape measure being shown in dashed lines and forming no part of the claimed design.

FIG. 5 is a back elevation view thereof.

FIG. 6 is a left side view thereof.

FIG. 7 is a front elevation view thereof.

FIG. 8 is a right side view thereof.

FIG. 9 is a front perspective view similar to FIG. 1 and showing our new design in an article marking position as tapped on top by a hammer (not shown).

FIG. 10 is a top plan view thereof.

FIG. 11 is a bottom plan view thereof.

FIG. 12 is alternate front perspective view thereof as connected to a tape measure to illustrate environment, the tape measure being shown in dashed lines and forming no part of the claimed design.

FIG. 13 is a back elevation view thereof.

FIG. 14 is a left side view thereof.

FIG. 15 is a front elevation view thereof; and,

FIG. 16 is a right side view thereof.
